UNITED STATES PATENT OFFICE.

LINUS WOLF, OF CHICAGO, ILLINOIS.

METHOD OF PRODUCING AND SEPARATING LIQUEFIED GAS.

1,274,970.

Specification of Letters Patent. Patented Aug. 6, 1918.

Original application filed December 3, 1913, Serial No. 804,333. Divided and this application filed May 31, 1916. Serial No. 100,809.

To all whom it may concern:

Be it known that I, LINUS WOLF, a citizen of the United States, residing at Chicago, county of Cook, State of Illinois, have invented an Improvement in Methods of Producing and Separating Liquefied Gas, of which the following description, in connection with the accompanying drawing, is a specification, like characters on the drawing representing like parts.

This invention relates to a novel method of producing a liquefied gas from distillation gas or natural gas. These gases contain various hydrocarbon constituents, some of which, such as gasolene or naphtha, are easily liquefiable, (that is, they can be liquefied at atmospheric pressure by a moderate refrigeration, or at normal temperatures by moderate pressure) and others of which are much more difficult to liquefy and require either high refrigeration or high pressure or both to effect the liquefaction thereof.

By means of the herein-described method, the hydrocarbon constituents which are relatively easy to liquefy are first separated out from the distillation or natural gases, and then the remaining liquefiable constituents are liquefied whereby a liquefied gas is produced which is free from the easily-liquefiable hydrocarbon constituents. A liquefied gas of this nature will readily vaporize and can be used for heating, lighting and power purposes.

In accordance with my improved method, the easily-liquefiable constituents are separated from the remaining constituents of the distillation or natural gas by mixing with said gas a similar gas at a very low temperature and in sufficient quantities to reduce the temperature of the distillation or natural gases to the point where the easily-liquefiable constituents thereof become liquid and can be separated therefrom.

In order to give an understanding of my invention, I have illustrated in the drawings an apparatus by which the method may be carried out, but I desire to state that the practice of the method is not limited to the particular type of apparatus herein shown, the latter being merely selected as one apparatus by which the method can be practised. The apparatus herein shown is claimed in my co-pending application Ser. No. 804,333, filed December 3, 1913, of which this is a division.

Figure 1 is a more or less diagrammatic view showing part of an apparatus by which my improved method may be practised;

Fig. 2 is a similar view showing the remainder of the apparatus.

In producing from natural or distillation gas a liquefied gas which is free from the easily-liquefiable constituents such as gasolene, it is the practice to subject the distillation or natural gas to a refrigerating process which is sufficient to liquefy the easily-liquefiable constituents, said constituents when thus liquefied being separated from the gas and the latter being then subjected to high pressure and severe refrigeration to effect the liquefaction of the less easily-liquefiable constituents. In accordance with my present invention the necessary refrigeration of the natural or distillation gas for the purpose of liquefying the easily-liquefiable constituents is prevented by commingling with the distillation or natural gas, constituents thereof in gaseous form, which constituents have a sufficiently low temperature so that when they are commingled with the gas said constituents cool the gas at a point where the easily-liquefiable constituents thereof will become liquefied. After the liquefaction in this manner of the easily-liquefiable constituents, they are separated from the remainder of the gas and the latter is subjected to high pressure and severe refrigeration to liquefy the remaining liquefiable constituents thereof. The method above briefly referred to will be better understood upon reference to the drawings which show an apparatus by which it may be carried out.

In the drawings, 1 designates generally a suitable retort in which distillation gases are formed by distillation of crude oil. This retort may have any suitable or usual construction. The distillation gases are taken from the retort through a pipe 2 and led into a cooling device 3 of usual construction by which the tar and other similar heavy products are separated. From the cooler 3 the gases are taken through a pipe 4 through a cooling apparatus 5 in which the gas is cooled to a point sufficient to liquefy the easily-liquefiable hydrocarbon constituents. The cooling in this apparatus is accomplished by mixing with the distillation gases a similar gas which has a very low temperature, this operation resulting in reducing the temperature of the distillation gases to a

point where the easily-liquefiable hydrocarbon constituents became liquefied.

The cooling device herein illustrated comprises a cooling chamber 6 into the lower end of which the pipe 4 leads, said cooling chamber having situated within it agitators or mixers 7 by which the gas passing therethrough is mixed or agitated. These mixers are shown in the form of blades 10 mounted on shafts 8 journaled in suitable bearings, and the shafts carry pulleys 9 which are connected by belts with some source of power, the construction being such that the adjacent agitators are rotated in opposite directions. The low temperature gases are preferably introduced into the cooling chamber at several points along its length. In the construction herein shown the cooling chamber has associated therewith at various points an annular spray device 10 provided with nozzles 11 extending through the wall of the chamber 6, said nozzles operating to deliver the gas into said chamber from all sides thereof. This gas is supplied to these spray devices 10 through a supply pipe 12. The low temperature gas which is thus used for cooling the distillation gases in the chamber 6 is distillation gas which has been previously liquefied and which has secured its low temperature by being expanded from a high pressure to the pressure of the distillation gases in the cooling chamber 6.

The cooling chamber 6 is placed in a casing 13 filled with suitable insulating material 14 so as to prevent any loss of heat by radiation. As the distillation gases pass through the cooling chamber 6 and are thus cooled by being mixed with the low temperature gases the easily-liquefiable hydrocarbon constituents, such, for instance, as gasoline or naphtha, become liquefied, and as they thus become liquefied they collect in a chamber or tank 15 having a sealed outlet pipe 16 that delivers into a collecting tank or receptacle 17. The object of the sealed outlet pipe is to prevent the admission of air to the chamber 15 while at the same time permitting the liquid to be freely discharged from the chamber 15 as it collects therein.

From the cooling chamber 6 the distillation gases which are not liquefied in the cooler are taken through a pipe 18 to a scrubber 19 of any usual construction by which the sulfur is removed, and from the scrubber the gases pass through a pipe 20, to a filter 21, and thence to a compressor 22 by which the gases are highly compressed, say to about fifteen to eighteen hundred pounds. From the compressor the compressed gases pass through a pipe 23 to a water cooler 24 which partially cools them, and from the cooler 24 the gases are taken to a refrigerating apparatus 26 in which they are cooled while under pressure to a

sufficient temperature to effect the liquefaction of substantially all the gases that it is desired to liquefy.

This refrigerating apparatus is in the form of a reverse current device, it comprising a coil 27 through which the compressed gases pass, and a reverse current coil 28 through which the refrigerating gases pass. From the refrigerating apparatus the gas passes into a collecting chamber 29 in which the liquefied gas accumulates. This collecting chamber 29 has a delivery pipe 30 connected thereto leading to a chamber 31 provided with a pressure gage 32, test cock 33, etc., and from this chamber the liquefied gas is delivered through a pipe 34 to a steel tank or bottle 35 in which it is stored for shipment.

The refrigerating medium that is used in the reverse current coil 28 of the refrigerating apparatus is liquefied gas taken from the collecting chamber 29. The chamber 31 has a pipe 40 connected thereto which is controlled by a suitable valve 41, and this pipe 40 leads to the reverse current coil 28 so that by opening the valve 41 some of the liquefied gas which is under high pressure expands into said pipe and the reverse current coil 28, such expansion producing the low temperature required for the liquefaction of the gases. After the refrigerating gases have passed through the refrigerating apparatus they are taken through a pipe 42 to the delivery pipe 12 and are delivered to the cooling chamber 6, these gases constituting the low temperature gases that are used for effecting the cooling of the distillation gases in the cooler 6.

Distillation gases produced from crude oil contain some hydrocarbons which are extremely difficult to liquefy, and these hydrocarbons will pass over into the collecting chamber 29 in a gaseous, rather than a liquid state. In order to continue the liquefying process and thus secure the liquefaction of some of these higher gases, I provide a refrigerating apparatus in connection with the collecting tank 29 which is constructed to continue the refrigerating process on the gases which accumulate in said collecting tank 29. For this purpose said tank is provided with an extension 43 in which the gases will accumulate, and this extension has associated therewith a refrigerating apparatus. In the illustrated construction this refrigerating apparatus comprises a casing 44 surrounding the extension 43, and provided with baffle-plates 45 to make a circuitous passage therethrough. The extension 43 has connected thereto at its upper end a pipe 46 leading around into the lower side of the casing 44, said pipe being controlled by a suitable valve 47. By opening the valve 47, the gases under high pressure in the extension 43 are expanded into the

casing 44, and thus produce a refrigerating action which reduces the temperature of the gases in said extension and causes liquefaction of a portion thereof. The gases which have passed through the casing 44 may be taken through a pipe 90 to a gasometer 48. I will preferably provide two pipes 46, each having a valve 47 therein so that in case one pipe or valve becomes frozen up, the other can be used. By this construction I can liquefy a much larger proportion of the distillation gases than is possible without the additional refrigerating apparatus in connection with the extension 43.

15 The proper operation of the compressor 22 requires that the pistons should be kept properly lubricated, and I have found that this can best be done by admitting to the gas which is to be compressed a certain 20 amount of moisture, the moisture providing the necessary lubrication. The compressor 22 will be water-jacketed to keep it cool, as usual in compressors, and I have shown the water jacket herein as provided with a valve 25 49 by which a proper quantity of water from the jacket can be admitted to the cylinder. A slight quantity is sufficient for this purpose. This water is converted into vapor by the heat of compression and is 30 delivered from the compressor with the gases through the pipe 23. It is necessary to remove this water from the gas before the latter is liquefied in the refrigerating apparatus 26, and to provide for this I employ a separating tank 25 connected to the water-cooling coil 24 and through which the 35 compressed gases pass on their way to the refrigerating apparatus 26. This collecting chamber 25 is somewhat in the nature of a trap, the pipe 50 from the coil 24 entering the top of the collecting chamber and extending part way to the bottom and the outlet 51 from the chamber being above the discharge end of the pipe 50. The moisture 40 in the gas will be condensed in the cooling apparatus 24 and will collect in the bottom of the collecting chamber 25. In order to draw this water off I provide a second chamber 52 connected to the lower end of the 45 chamber 25 by a pipe 53 having a valve 54 therein, and the chamber 25 is provided with a drip cock 55. When water accumulates in the tank 25 the valve 54 is opened and the pressure will force the water around into the tank 52 after which the valve 54 may 50 be closed and the water allowed to drain out through the tank 52 through the drip cock 55.

55 In order to regulate the degree of refrigeration attained in the refrigerating apparatus 26, I have provided a by-pass 60 controlled by a valve 61 through which the refrigerating medium or a part thereof can be shunted around the counter-current coil 28. In order to still further regulate this

refrigerating action, I have provided means whereby the gas which is expanded in the counter-current coil may be taken either from the bottom of the collecting tank 29 or from a point some distance from the bottom. The liquid at the bottom of the collecting tank 29 will have less of the gaseous constituents therein than that toward the upper part of the tank because as the liquefied gas is delivered to the tank 29 from the reverse current coil 28, the unliquefied gaseous constituents will tend to rise in the tank so that the liquid in the upper portion of the tank will contain a greater proportion of the gaseous constituents than that in the lower part of the tank. Accordingly the specific gravity of the liquid will be greater at the bottom of the tank than it is part way up in the tank. 63 is a pipe which leads into the bottom of the tank 29 and terminates some distance above the bottom, said pipe leading to and communicating with the pipe 40 and being controlled by a suitable valve 64. By means of the two valves 41 and 64 the liquid in the counter-current coil 28 may be taken either from the bottom or from the middle portion of the tank 29, and by this means the degree of refrigeration can be controlled.

95 I have shown at 70 an internal combustion engine for operating the compressor. This is supplied with fuel from the gasometer 48 by means of a pipe 71. The tank 52 is also connected to the pipe 71 by means of a pipe 72 so that any surplus gas accumulating in 100 said tank may be delivered to the motor.

The outlet of the water cooler 24 is connected to the jacket of the internal combustion engine 70 and thus the water which is used in the cooler is also made use of for 105 cooling the engine. Under some circumstances it may be desirable to use warm water in the jacket of the compressor so as to avoid the possibility of the gas becoming cooled in the compressor to a point where 110 some of the constituents will become liquefied, for the presence of liquid in the compressor will interfere with its operation. It is desirable to remove some of the heat of compression in the condenser, but not to 115 cool the gas to the point where any portion of it will become liquefied.

The apparatus which has been above described in some detail is designed for use in the treatment of the distillation gas. If 120 natural gas is being treated, no retort will be necessary for the production of the gas, as the gas could be piped directly from the supply to either the cooling device 3 or the cooling device 5.

125 From the above it will be seen that my improved process consists in commingling with distillation gas or natural gas constituents thereof at a sufficiently low temperature and in sufficient volume to effect 130

the cooling of the gas to a point where the easily-liquefiable constituents thereof become liquefied, and then separating the liquid thus obtained from the gaseous constituents and subjecting said gaseous constituents to pressure and refrigeration to effect liquefaction thereof.

I wish to state that although I have described in some detail an apparatus capable 10 of carrying out my improved process, yet it will be obvious that the process is not limited in its practice to the particular apparatus herein shown.

I claim:

- 15 1. The process of producing liquefied constituents of a hydrocarbon gas, such as distillation gas or natural gas, which consists in passing the hydrocarbon gas through a heat-insulated chamber, introducing into 20 said chamber gas constituents of said hydrocarbon gas at a sufficiently low temperature and in sufficient volume to effect the cooling of the hydrocarbon gas to a point where the easily-liquefiable constituents thereof become liquefied, agitating the gas as it passes through said chamber, separating the liquid thus obtained from the gaseous constituents, and then liquefying said gaseous constituents.
- 25 2. The method of treating a hydrocarbon

gas such as distillation gas or natural gas which consists in passing the hydrocarbon gas through a heat-insulated chamber, introducing into said chamber gas constituents of said hydrocarbon gas at a sufficiently low temperature and in sufficient volume to effect the cooling of the hydrocarbon gas to a point where the easily-liquefiable constituents thereof become liquefied, agitating the gas as it passes through said chamber, and separating the liquid thus obtained from the gaseous constituents.

3. The process of producing liquefied constituents of a hydrocarbon gas, such as distillation gas or natural gas, which consists in passing the hydrocarbon gas through a heat-insulated chamber, introducing into said chamber at different points along its length gas constituents of said hydrocarbon gas at a sufficiently low temperature and in sufficient volume to effect the cooling of the hydrocarbon gas to a point where the easily-liquefiable constituents thereof become liquefied, agitating the gas as it passes through said chamber, separating the liquid thus obtained from the gaseous constituents, and then liquefying said gaseous constituents.

In testimony whereof, I have signed my name to this specification.

LINUS WOLF.
